UNITED STATES PATENT OFFICE

CHARLES D. TURLINGTON, OF LILLINGTON, NORTH CAROLINA, ASSIGNOR OF ONE-HALF
TO ERNEST F. YOUNG, OF DUNN, NORTH CAROLINA

TRACE-CHAIN HOOK

Application filed August 21, 1928. Serial No. 301,045.

This invention relates to harness and particularly to a hook or application to the back band of the harness for the purpose of supporting the trace chain.

5 The general object of the invention is to provide a trace chain supporting hook which may be readily applied to the back band and is so constructed that it will offer no obstruction or projection which is likely to rub or 10 gall the animal.

A further object is to provide a back band hook which may be detachably engaged with any one of the links of the trace chain so as to permit the back band to be adjusted 15 nearer to or further from the crupper and the hook to engage with the trace chain at any adjusted point.

Another object is to provide a device of 20 this character which, when in use, cannot accidentally open to release the trace chain.

My invention is illustrated in the accompanying drawings wherein—

Figure 1 is a face view of a back strap with my trace chain support and latch attached thereto;

Figure 2 is a rear elevation of the trace chain support;

Figure 3 is a vertical sectional view thereof; and

30 Figure 4 is a side elevation thereof.

Referring to these drawings it will be seen that the back band hook comprises a body designated generally 10, and formed of two end walls 11 and with a front downwardly and rearwardly curved wall 12. The upper ends of the end wall above the upper edge of the front wall 12 are connected by a transverse bar 13 affording means whereby a canvas or leather loop may be engaged with the 40 hook to support the hook.

The front wall 12 is carried downward and rearward to the rear of the hook and has cast integrally thereon the trace chain supporting loop 14. The rear wall of this loop extends straight downward from the body and this rear wall of the loop is vertically slotted at 15. This slot extends downward to the lowest portion of the loop and extends up 50 through the bottom or lower wall of the body

10, which lower wall is formed by the inward extension of the front wall 12.

Disposed between the end walls 11 and forming the rear wall of the hollow body is a plate 16 having outwardly projecting ears 17 which fit against the end walls of the body and which are pivoted thereto by means of a pivot pin 18. Formed integrally with this plate 16 is a tongue 19 which when closed fills up the slot 15, the outer face of this tongue 19 conforming in curvature to the curvature of the loop 14. This tongue is provided above its lower end with an inwardly projecting tooth 20 which when the tongue is closed into the slot 15 approximates the front wall or outer wall of the loop 14. Surrounding the pivot 18 is a coil spring 21 formed of a single piece of wire, the middle thereof being formed to provide a bight portion 22 which bears against the front wall 11. 60 65 70

The ends of the wire extend upward against the plate 16 adjacent its upper edge. The shank of the tongue 19 extends upward above the lower edge of the plate so as to form a rib 23 between the two coils of wire. The 75 spring urges the tongue 19 into place flush with the exterior face of the loop 14.

It will be seen that when this device is in use it is preferably attached to the back band A of the harness by means of a loop B of leather, canvas or the like passing around the cross bar 18. The back band hook being perfectly flat and smooth on its inside face has no projection which can rub against the animal and form a sore. When the trace 80 chain is placed through the loop 14 it is engaged by the tooth 20 and the strain on the trace chain keeps the inner face of the trace chain hook lying flat against the animal so that there is no possible chance for the tongue 90 95 100 19 to accidentally open, this being further prevented by the action of the spring 21. When it is desired to open the tongue and release the tooth 20 from engagement with the trace chain either to entirely remove the trace chain or adjust it, this may be readily done by engaging the finger nail with the extremity of the tongue 19 and pulling outward on the loop 14 and pushing inward on the end of the tongue, thus relatively retract-

ing the tooth from projecting through the loop.

This device supports the trace chain and prevents it from getting slack, and by adjusting the trace chain within the loop the plow or other implement being pulled may to a large extent be controlled. Thus by shortening the chain between the loop or hook the plow has a tendency to pull the point of the plow up and thus secure shallow plowing, and by increasing this distance, deeper plowing may be secured.

It will be understood that the back band is also to be adjusted nearer to or further from the horse's crupper and that this will change, of course, the angle of the trace with regard to the plow and that the back band is held in this relation to the trace by the engagement of the tooth with the corresponding link on the trace.

Preferably the body of my hook or loop and the pivoted plate and tongue will be cast, but I do not wish to be limited to this nor to an of the details of construction except as stated in the accompanying claims.

What I claim is—

1. A trace chain hook comprising a hollow body portion having a depending loop, the body and the loop on their rear sides being open, a plate having a depending inwardly curved tongue, the plate constituting the rear wall of the body and being pivoted thereto and the tongue when closed conforming to and fitting the opening in the rear portion 30 of the loop, the tongue being provided with a forwardly projecting tooth extending across the loop when the tongue is closed and adapted to engage a link of the trace chain, and a spring urging said tongue into its position.

2. A trace chain hook comprising a hollow body open at its rear face and at its upper end having a cross bar, the lower end of the body being formed to provide an integrally 45 depending loop, the rear portion of the loop being longitudinally slotted down to the lower end thereof, said slot opening into the body, a plate forming the rear wall of the body and having inwardly projecting ears 50 pivoted to the end walls of the body, the plate having an integral downwardly extending inwardly curved tongue when closed adapted to fit into the opening in the rear of the loop and conforming to the shaft of the loop, the tongue having a tooth projecting across the loop and adapted to engage a spring within the body urging the tongue to a closed position in the loop.

In testimony whereof I hereunto affix my
60 signature.

CHARLES D. TURLINGTON.
